UNITED STATES PATENT OFFICE.

CHARLES V. PECKHAM, OF CHICAGO, ILLINOIS, ASSIGNOR OF TWO-THIRDS
TO JOSEPH H. DODSON AND LOUIS S. McMILLAN, OF CHICAGO, ILLINOIS.

SAFE.

SPECIFICATION forming part of Letters Patent No. 702,883, dated June 17, 1902.

Application filed October 26, 1901. Serial No. 80,074. (No model.)

To all whom it may concern:

Be it known that I, CHARLES V. PECKHAM, a citizen of the United States, residing in Chicago, in the county of Cook and State of Illinois, have invented a certain new and useful Improvement in Safes, of which the following is a specification.

This invention relates particularly to small safes designed more especially for use in receiving household articles, papers, and other small articles of value, and is intended principally for use in houses, rooms, or offices, but is well adapted for use and can be used in safety-deposit vaults where it is desired to have a small safe containing several compartments.

The object of the invention is to construct a safe of the character described which will be very compact, strong, and durable, and which will occupy but little space and be well adapted for the purpose intended, and which can be securely fastened wherever it is desired to have the safe located, and which will be a safe protection against fire and against removal by housebreakers; and the invention consists in the features of construction and combinations of parts hereinafter described and pointed out as new.

In the drawings illustrating the invention, Figure 1 is a front elevation with a portion broken out at one edge and into the door, and Fig. 2 a top or plan view with the outer wall broken away and in section and with the inner wall in section and broken away at one corner.

The safe is constructed of an outer shell or casing having a cylindrical wall A and a solid end wall A', and on the under side the cylindrical shell A is turned so as to form a neck or base A² with a cross-plate a², forming a rest or support for the safe. The front end of the outer shell or casing has a flange a on the inside, extending inward from which is an annular rim or lip a', forming the opening for the door. The body or wall A, end wall A', neck or base A², flange a, rim a', and plate a², forming the outer shell or casing as a whole, are cast or formed integral from any suitable metal. An inner shell or casing is located within the outer shell or casing, and the inner shell or casing is formed of a body

or annular wall B and a closed end or head B', and the opposite end has a flange b standing inward and an annular rim or lip b' outwardly flaring from the flange b and terminating in a rim or flange b², outwardly extending from the rim or lip b', as shown in Fig. 2. The body or annular wall B, end or head B', flange b, annular rim or lip b', and rim or flange b² are cast or otherwise formed integral one with the other from any suitable metal, and the exterior diameter of the inner shell or casing is such as to admit of the insertion thereof through the opening for the door in the end of the outer shell or casing. The door is formed of an outer wall or plate C and an inner wall or plate C', with a filling-space between them. The outer wall or plate has on its inner face around its periphery an annular wall c, having an exterior face to fit closely the interior face of the rim or lip a' when the door is closed. The annular wall c terminates in a shoulder c², extending out from which is an annular rim or lip c', the shoulder c² and the rim or lip c' coinciding with and fitting closely against the flange or rim b² and rim or lip b' when the door is closed. The inner wall or plate C' is cast integral with the outer plate or wall and its annular shouldered wall and rim or lip or can be made separate and suitably secured to the rim or lip b² by rivets or otherwise, so as to be, in effect, a part thereof. The door is provided with a combination-lock D of any suitable construction, operating to retain the bolt projected and to release the bolt for withdrawal, and for moving the bolt a handle d is provided, connected with the bolt d' in any usual and well-known manner. The bolt d' passes through the annular wall or rim c and when projected enters an opening a³ therefor in the rim or lip a', as shown in Fig. 2. The flange or rim a of the main or outer shell or casing has on its exterior face an ear or eye f, and the door on the exterior face of its plate C has two ears or eyes f', spaced apart to receive between them the eye or ear f, and when the ears or eyes f and f' are in alinement a pivot-pin f² is inserted, holding the door as a whole on the outer shell or casing, so that it can swing on the hinge to open and close the door.

The interior of the inner shell or casing in

the arrangement shown is divided into chambers or compartments E by horizontal and vertical plates or partition-walls e, each chamber or compartment receiving thereinto any article or articles that it is desired to place in the safe for keeping. The space between the outer shell or casing A and the inner shell or casing B at the sides and rear end is packed with a suitable filling F, which filling may be a non-conductor of heat, so as to insure preservation of the contents of the safe in case of fire, and the space between the inner and outer walls or plates of the door is also packed with a filling F' of the same character as the filling between the two shells or casings. The construction shown has extending from the under side or bottom of the inner shell or casing a series of bolts G, the heads of which are entered into recesses or countersinks g and the stems of which pass through the bottom plate or support a^2 and can be screw-threaded for the reception of nuts or otherwise formed, so as to firmly attach the safe to a floor, shelf, or other support. A bolt or series of bolts H extend from the rear end wall of the inner shell or casing, with the head or heads of the bolts in a depression or countersink h in the end head or wall, with the stem passing through the rear end head or wall of the outer shell or casing, and the stem can be screw-threaded to receive a nut or otherwise formed, so as to firmly attach the safe at its rear end or side to a rigid backing or support. It will be seen that by means of the bolts or stems G and H the safe can be securely fastened down, so that it cannot be readily removed, thus preventing the safe being carried away except by cutting or breaking the fastened bolts or stems. The safe as a whole can be cast from any suitable metal, making its construction exceedingly cheap, and at the same time the construction is one which will make the safe fireproof and when bolted or fastened down not capable of easy removal. The safe is well adapted for placement in a room, office, or otherwise where it is desired to have security against loss by fire of valuables or where it is desirable to lock valuables up for security. The safe can be of different sizes to suit the requirements of the place in which it is to be located and used, and by providing the interior of the inner shell or casing with chambers the safe can receive articles of different characters which can be kept separate one from the other. The safe furnishes a security for articles locked therein against fire and against ready removal except by the party having the combination, and will be found very desirable and useful for the safe keeping of articles of value and will not occupy much space in the place where it is located.

What I regard as new, and desire to secure by Letters Patent, is—

1. In a safe, the combination of an outer shell or casing consisting of a circular or tubular body or wall provided on one side with a flat seating or supporting face, a closed end head or wall and an end flange forming an open end for the shell or casing, an inner shell or casing consisting of a circular or tubular body or wall, a closed end head or wall, a turned end flange and rim forming an open end for the shell or casing, and a door hinged at one side to the end flange of the outer shell or casing and having a circumferential wall or rim fitting the open ends of the outer and inner shells or casings, substantially as described. 70
2. In a safe, the combination of an outer shell or casing having a circular or tubular body or wall with a neck or base, a closed end head or wall and an end flange inwardly turned forming an open end for the shell or casing and all made integral, an inner shell or casing having a circular or tubular body or wall, a closed end head or wall and an end flange and rim forming an open end for the shell or casing and all made integral, a door 80 having an outer plate or wall and an inner plate or wall with a circumferential stepped wall and rim between them fitting the open ends of the outer and inner shells or casings, and a hinge for the door to the open end of 90 the shell or casing, substantially as described. 95
3. In a safe, the combination of an outer shell or casing, an inner shell or casing, a base for the outer shell or casing and on which the safe is supported, a countersink in the bottom of the inner shell or casing, and a bolt having its nut or head end entered into the countersink of the inner shell or casing and having its body passing through the wall of the countersink and the base for fixedly securing the safe in position, substantially as described. 100
4. In a safe, the combination of an outer shell or casing having a closed end wall, an inner shell or casing having a closed end wall, a base for the outer shell or casing on which the safe is supported, a countersink in the closed end wall of the inner shell or casing, a countersink in the bottom of the inner shell or casing, a bolt having its nut or head end 110 entered into the countersink of the end wall of the inner shell or casing for the stem to pass through the wall of the countersink and the end wall of the outer shell or casing, and a bolt having its nut or head end entered into 115 the countersink in the bottom of the inner shell or casing for its stem to pass through the wall of the countersink and the base and securely fasten the safe in a fixed position, substantially as described. 120
